UNITED STATES PATENT OFFICE.

JAMES BRENTON, OF WAUKEGAN, ILLINOIS, ASSIGNOR TO NORTHERN BRASS MANUFACTURING COMPANY, OF WAUKEGAN, ILLINOIS, A CORPORATION OF ILLINOIS.

QUICK-OPENING FAUCET.

1,210,893.

Specification of Letters Patent. Patented Jan. 2, 1917.

Application filed March 15, 1915. Serial No. 14,459.

To all whom it may concern:

Be it known that I, JAMES BRENTON, a citizen of the United States, and a resident of Waukegan, county of Lake, and State of Illinois, have invented certain new and useful Improvements in Quick-Opening Faucets, of which the following is a full, clear, and exact description.

The invention relates to faucets or cocks of the quick opening type and which are usually provided with multiple screw threads of sharp pitch so that the valve can be opened and closed by turning the valve operating stem through a partial rotation. The valve of such a quick opening faucet or cock is arranged on the discharge side of the valve seat and is apt to be opened accidentally by the pressure of the water supply and particularly after the operating parts become loosened or worn.

The present invention seeks to provide improved means for frictionally holding the valve against accidental opening and consists in the features of improvements herein-after set forth, illustrated in the preferred form in the accompanying drawings and more particularly pointed out in the appended claims.

In the drawings, Figure 1 is a view partially in vertical section, of the improved faucet or cock. Fig. 2 is a section on the line 2-2 of Fig. 1.

The faucet or cock comprises a suitable casing 1 having a partition 2 provided with a port 3. The partition is provided on its upper or discharge side with a raised valve seat 4 about the port 3. Preferably also, an annular recess 5 is provided in the upper face of the partition extending about the valve seat. Above and in line with the port, the casing is provided with an upwardly extending cylindrical portion 6.

A valve 7 is arranged on the discharge side of the valve seat and its lower end is arranged to extend within the recess 5 of the partition 2. Preferably, as shown, the lower end of the valve is provided with a washer 8 which is held in place by a screw 9 and which is arranged to engage the valve seat 4.

In the preferred form shown, the enlarged upper end of the valve is provided with external screw threads 10 which coöperate with internal threads 11 formed upon the upwardly extending portion 6 of the casing.

These threads are multiple (quadruple in

the form shown) and are of sharp pitch so that the valve can be opened and closed by turning it through a partial rotation.

In the preferred construction set forth the valve stem 12 is separated from the valve and is provided with a square lower end portion 13 which fits within the correspondingly shaped socket or bore 14 in the upper enlarged portion of the valve. Preferably also, the valve stem is held against vertical movement and for this purpose is provided with an integral collar 15 and a cap-nut 16 coöperates with the collar to prevent the vertical movement of the valve stem. As shown, the cap-nut 16 is threaded upon the upper end of the extension 6 and a body of packing material 17 within the cap-nut extends over the upper edge of the extension 6 and against the valve stem to form tight joints therewith. The collar and the upper portion of the cap-nut are preferably conical in form as shown.

Means are provided for frictionally holding the valve stem in any set position to thereby prevent any accidental movement or opening of the valve. For this purpose a series of washers are mounted upon the valve stem, one of the washers being connected to rotate with the stem, and the other washer or washers being held in fixed position and in frictional contact with the rotatable washer. Preferably, as shown, three flat metal washers 18, 19 and 20 are mounted upon the squared portion of the valve stem immediately below the collar 15 and these washers are arranged within an internal recess or seat in the upper end of the cylinder extension 6. The intermediate washer 19 is provided with a square opening which loosely fits the squared portion of the valve stem so that this washer rotates with the stem. The other washers 18 and 20 are provided with round central openings and are clamped in fixed position between the packing 17 in the cap-nut 16 and the upper end of the extension 6. In this way the fixed washers 18 and 20 bear with sufficient friction upon the washer 19 to prevent the accidental rotation of the valve stem 18 and the accidental movement of the valve.

The collar 15 of the valve operating stem is clamped between the upper washer and the packing 17 within the cap-nut 16 so that the valve stem is held against vertical movement, but the rotation of the valve stem, of

course, opens and closes the valve. The collar 15 is considerably smaller than the upper washer so that the packing is pressed by the cap-nut into engagement with the face of the upper washer to hold it in fixed position. The engagement of the lower washer 20 with the shoulder at the upper end of the screw thread in the extension 6 will hold it in fixed position. The intermediate washer 19 which rotates with the valve stem fits the same somewhat loosely so that it can be gripped with considerable friction between the fixed washers 18 and 20 without causing undue binding between the rotatable valve stem and the fixed parts of the faucet. The arrangement prevents undue wear between the movable and fixed parts. The lower end of the valve stem also fits rather loosely within the bore of the valve so that the latter is self-adjusting upon its seat and so that there will be no undue binding between the screw threads of the valve and of the casing.

The valve stem is provided at its upper end with a suitable handle 21 held in place by a screw 22.

It is obvious that numerous changes may be made in the details of structure without departure from the essentials of the invention as defined in the claims.

30 I claim as my invention:—

1. A faucet of the quick opening type having a rotatable valve-operating stem, a washer loosely mounted on said stem but connected to rotate therewith, and means held against rotation on said faucet for frictionally engaging said washer.

2. A faucet comprising a casing having a valve seat, a valve on the discharge side of said seat having quick acting threads, a rotatable stem for operating said valve, a washer loosely mounted on said stem but connected to rotate therewith, a cap-nut for said casing, and means held against rotation between said cap-nut and casing for frictionally engaging said washer.

3. A faucet comprising a casing having a valve seat, a valve on the discharge side of said seat having quick acting threads, a rotatable stem for operating said valve having a collar thereon, and a washer loosely mounted on said stem but connected to rotate therewith, said casing having means coöperating with said collar to hold said stem against vertical movement and for frictionally engaging said washer.

4. A faucet of the quick opening type having a rotatable valve-operating stem, a plurality of metal washers separate from said

stem but mounted thereon, one of which is connected to rotate with said stem, and means on said faucet for clamping the other washer or washers against rotation and in frictional contact with said rotatable washer.

5. A faucet of the quick opening type having a rotatable, valve operating stem, three metal washers mounted on said stem, the intermediate washer being connected to said stem to rotate therewith, and means for clamping the other washers against rotation and in frictional contact with said intermediate washer.

6. A faucet comprising a casing having a valve seat, a valve on the discharge side of said seat, a rotatable stem for operating said valve, a plurality of washers loosely mounted on said stem, one of which is connected to said stem to rotate therewith, and a cap-nut on said casing arranged to clamp the other washer or washers against rotation and in frictional contact with said rotatable washer.

7. A faucet comprising a casing having a valve seat, a valve on the discharge side of said seat, a rotatable stem for operating said valve having a collar thereon, a plurality of metal washers loosely mounted on said stem beneath said collar, one of which is connected to said stem to rotate therewith, and a cap-nut on said casing coöperating with said collar to hold said stem against vertical movement and for clamping the other washer or washers against rotation and in frictional contact with said rotatable washer.

8. A faucet comprising a casing having a valve seat, a valve on the discharge side of said seat, a rotatable stem for operating said valve having a collar thereon, a series of three metal washers loosely mounted on said stem below said collar, the intermediate washer being connected to said stem to rotate therewith, and a cap-nut on said casing coöperating with said collar to hold said stem against vertical movement and clamping the other washers against rotation and in frictional contact with said rotatable washer.

9. A faucet of the quick opening type having a rotatable valve-operating stem, a friction washer loosely mounted on said stem but connected to rotate therewith, and co-operating friction members held against rotation on said faucet for frictionally gripping said washer between them.

JAMES BRENTON.
